COMBINATION BED AND CHAIR

Isaak Karish, Chicago, Ill.

Application November 5, 1938, Serial No. 238,999

5 Claims. (Cl. 155—49)

This invention relates to a bed, and more particularly to a collapsible combination bed, cot and beach chair adapted to afford a portable article of collapsible furniture conveniently lending itself for camping, as an auxiliary household article of furniture, a deck chair or beach chair, and for many other purposes. This improved combination article of furniture is of the collapsible or knock-down type of simple and effective construction, consisting of a collapsible base or supporting section and a collapsible top or bed section removably engageable on the base section and extendable for use as a bed, cot or chair.

15 It is an object of this invention to provide an improved, simplified and inexpensive type of combination bed and chair of the collapsible type, constructed in collapsible sections for convenient storage in a comparatively small space or 20 for packing in a suitcase or carrier.

It is also an object of this invention to provide a collapsible type of combination bed and reclining chair including a mattress or top section, the ends of which are adapted to be adjusted to convert the folding bed into a deck or beach type chair.

It is a further object of this invention to provide an improved type of collapsible bed wherein the mattress or top section is adapted 30 to be removably attached to a collapsible base or bottom section from which it is adapted to be completely separated when it is desired to fold up the top and bottom sections for the purpose of storing the same in a storage space or carrier.

It is a further object of this invention to provide a collapsible type of bed adapted to be readily converted into a chair if desired, said bed consisting of a collapsible supporting section adapted to have removably engaged thereon a collapsible mattress or top section, the end portions of which are adapted to be extended for use and be supported by end section legs, permitting the structure to be used as a camp bed or as a temporary sleeping structure.

45 It is furthermore an object of this invention to provide a collapsible type of bed constructed of independently collapsible sections, which when collapsed are adapted to be stored in a comparatively small space and which furthermore may be opened up and attached to one another to form a complete bed or cot easily convertible into a reclining chair by the adjustment of said leg bearing end sections.

55 It is an important object of this invention to

provide an improved, simplified and inexpensive article of furniture, of the knock-down or collapsible and portable type, adapted when in collapsed form to be conveniently and quickly packed within a suit case or carrier and furthermore adapted, when opened up for use, to be readily and conveniently assembled to form a bed which may be easily converted into an invalid chair, a beach chair, a deck chair or the like.

Other and further important objects of this invention will be apparent from the disclosures in the specification and the accompanying drawings.

The invention (in a preferred form) is illustrated in the drawings and hereinafter more fully described.

On the drawings:

Figure 1 is a side elevational view of an improved combination bed and chair embodying the principles of this invention and illustrating in dotted lines the convertibility of the bed into a chair.

Figure 2 is a top plan view of a suitcase or carrier in open position, containing in one side thereof the collapsed sections comprising the bed structure, said suit case carrying on the opposite side thereof a collapsible type of chair.

Figure 3 is an enlarged fragmentary side elevational view of one of the front corners of the bed base section where it joins the front end of the intermediate section of the bed top unit or mattress section.

Figure 4 is a top plan view of the base or supporting section of the bed in collapsed form.

Figure 5 is a top plan view of the base or supporting section in set up position ready for use.

Figure 6 is an enlarged fragmentary detail section taken on the line VI—VI of Figure 3.

Figure 7 is a fragmentary detail sectional view taken on the line VII—VII of Figure 6.

Figure 8 is a top plan view of the bed top unit of the article of furniture, in compact collapsed form ready to be placed in a suit case or carrier as illustrated in Figure 2.

Figure 9 is a top plan view of the bed top unit partly opened up, from the position illustrated in Figure 8, and showing part of the opening up operation in dotted lines.

Figure 10 is a bottom plan view of the bed or mattress section of the article of furniture, completely opened up and ready to be locked in engagement upon the base or supporting section illustrated in Figure 5.

Figure 11 is an enlarged fragmentary side elevational view of the end portion of the head section of the bed when in open position.

Figure 12 is an enlarged fragmentary bottom plan view taken on the line XII—XII of Figure 11, with parts shown in section.

As shown on the drawings:

The improved collapsible and convertible article of furniture embodying this invention is of the combination bed and chair type, normally adapted when not in use to be carried in collapsed form within a suit case or carrier along with other articles of collapsible furniture, such as chairs, as illustrated in Figure 2, which discloses a convertible type of suit case or carrier consisting of two integrally connected sections 1 and 2. The suit case or carrier is of the convertible type, whereby the suit case may be opened up and used as a table or the like of the type illustrated and claimed in my co-pending application for patent entitled "Table and carrying case," filed on even date herewith, Serial No. 238,998.

Each of the case or carrier sections 1 and 2 has mounted therein a pair of collapsible legs 3 which are normally folded within the case sections 1 and 2, as illustrated in Figure 2. The collapsible and portable type of combination bed and chair embodying the present invention is normally adapted to be collapsed in compact separate sections, as illustrated in Figures 4 and 8, permitting the same to be placed side by side in collapsed form within a section of the suit case, as illustrated in Figure 2, to occupy a comparatively small amount of space, to permit the bed to be stored away when not in use and also permitting the collapsed bed to be transported.

The improved combination bed and chair consists of two units adapted when in collapsed form to be entirely separated from one another and furthermore adapted to be interlocked with one another to form a joint article of collapsible furniture. The base or supporting unit of the article of furniture comprises a pair of side rails or bars 4 constructed of wood or other suitable material. Each of the side rails 4 has secured on each end thereof, by means of a screw 5 or the like, a metal end casting comprising a side or outer wall 6, a top flange 7, a bottom flange 8, and an end wall 9. Integrally formed on the outer face of the lower corner of the side plate 6 on each of the castings is a leg stop or abutment lug 10. The side wall 6 on each of the castings is provided with a leg bolt opening and a leg bolt slot 11. The bottom flange 8 of each of the castings is provided with a guide slot 12 (Figure 6). Also provided on the side wall 6 of each of the castings is an inverted T-slot 13 (Figure 3), the shank end of which projects upwardly and opens through the top flange 7 to communicate with a slot or notch 14.

Provided in the top and bottom flanges 7 and 8 of each of the corner castings of the base unit are bolt openings. Integrally formed on the inner surface of each of the casting top flanges 7 is a boss 15, positioned to project into a recess or notch provided on the top surface near each end of the side rails 4 to assist in preventing the side rails from being pulled out of the corner castings.

Integrally supported against the outer face of the side plate 6 of each of the corner castings by means of a supporting bolt 16, is a base leg 17, which when in vertically supporting position contacts the stop 10 to limit the swing of the leg. To prevent the leg 17 from swinging back to a closed position away from the stop 10, each of the

corner castings has slidably engaged therein a transversely projecting lock bolt 18 adapted to slide outwardly through the slot 11. Integrally formed on the bottom edge of each of the locking bolts 18 is a downwardly projecting extension or finger 19 which projects downwardly through the guide slot 12 in the bottom flange 8, thereby providing an arrangement for limiting the shifting of the lock bolt 18. To assist in holding the lock bolt in position, a spring-controlled pin or stud 20 is mounted in each end of the side rails 4 (as clearly illustrated in Figure 7). When the lock bolt 18 is projected outwardly, as illustrated in Figure 6, a base leg 17 is engaged between the stop 10 and the bolt 18 to prevent pivotal swing- 15 ing of the leg in either direction.

Engaged through the bolt openings of the corner casting top and bottom flanges 7 and 8 respectively is a bolt 21. Pivotally supported on each of the bolts 21 within the corner casting is one end of an end brace rail or transverse member 22 constructed of wood or other suitable material. The opposite end of each of the transverse or end brace rails 22 is pivotally connected by means of a hinge 23 to the inner end of another end brace rail or member 22, the outer end of which is pivotally connected by means of a bolt 24 to an opposite corner casting. The two hingedly connected transverse brace rails 22 are arranged in pairs at each end of the base unit 30 and form transverse braces for holding the side rails properly spaced apart when the base unit is set up, as illustrated in Figure 5.

For the purpose of preventing the hingedly connected transverse braces 22 from accidentally collapsing, each of the brace rails 22 is provided with a recess 24 in which a gravity controlled latch bar 25 is pivotally supported at one end by means of a pivot pin or bolt 26, as illustrated in Figure 7. The opposite end of the pivoted latch 40 bar or bolt 25 has one corner thereof notched as at 27, forming a contact or stop pin 28 adapted to drop into contact with the inner face of the bottom flange 8 of a corner casting when the brace rail 22 is in bracing position at substantially right angles to the side rail 4. The notch 27 in the latch bolt 25 permits the latch bolt to drop over the inner edge of the flange 8 to position the latch bolt 25 in an inclined position, as shown in Figure 7, to act as a brace preventing the accidental collapsing of the hingedly connected brace rails 22.

To brace the lower end of the leg 17 against spreading outwardly away from the side of the base section when the same is set up for use, the lower ends of the two legs at each end of the base unit are connected by means of a flexible brace strap 29 constructed of leather, canvas, belting or other suitable material and having the ends thereof bent around the lower portions of the legs 17 and secured thereto by means of nails or other suitable fastening devices. It will thus be seen that the combination article of furniture includes a base or supporting unit, as illustrated in Figures 4 to 7, inclusive, adapted normally to be collapsed and folded into a compact form, as illustrated in Figure 4, to store the same in a comparatively small amount of space or to pack the same into a suit case, as illustrated in Figure 2. The base unit may be readily opened up 70 for use by first swinging the supporting legs 17 downwardly from the positions illustrated in Figure 4 at right angles to the side rails 4 and against the stop members 10, after which the shiftable latch bolts 18 are moved from the dot- 75

ted line positions shown in Figure 6 into the full line positions, to hold the supporting legs 17 properly braced against accidental collapsing.

After the legs 17 have been dropped into supporting position, the two side rails 4 are moved apart to their full amount, thereby causing the hingedly connected transverse brace rails 22 to swing to the full line positions illustrated in Figure 5, so that the two brace rails 22 at each end of the base unit are in substantial alignment with one another. In the open position of the two transverse brace rails, the gravity-controlled latch bolts or bars 25 are adapted to drop downwardly into the full line position illustrated in Figure 7 to engage the bottom flanges 3 of the respective corner castings to hold the hingedly connected transverse brace rails 22 against accidental collapsing. With the transverse brace rails in extended position, as illustrated in Figure 5, the flexible brace straps 29 are opened up into full position for use and are held stretched across the front and rear ends of the base unit to brace the lower portions of the legs 17. The set up base or supporting section is now ready to have the top or bed unit releasably engaged thereon, as illustrated in Figure 1, to complete the assemblage.

Referring now to Figures 8 to 12, inclusive, which illustrate in detail the various features of the top or bed section, consisting of a mattress unit constructed of a strip of canvas or other similar strong material. The mattress strip comprises a wide middle or intermediate main or seat section 30, a head or chair back section 31, and a foot or leg section 32 which is narrower than the head section 31. The head section 31 is slightly narrower than the middle section 30, as clearly illustrated in Figure 10. The outer end of the head section 31 of the mattress unit is provided with a suitable hem at 33, leaving an end loop 34 for removably receiving a head dowel rod or bar 35, the ends of which project beyond the sides of the loop 34 for engagement in side frame members, as hereinafter more fully described. The outer end of the mattress foot section 32 is also provided with a hem 33, forming a loop portion 34 for removably receiving a foot dowel rod or bar 36, the ends of which project for engagement in the side frame members, as hereinafter more fully described.

Disposed longitudinally along each of the side margins of the mattress strip are side frame units, each comprising an intermediate rail 37 constructed of wood or other suitable material, the outer side of which is provided with a longitudinal groove 38 (Figure 3) for the reception of a clamping strip 39 for securely holding the side margin of the mattress center section 30 clamped in the groove 38. The clamping strip 39 is held in position by means of screws 40 or other suitable devices. For the purpose of mounting the mattress unit upon the base supporting unit of the device, each of the intermediate side frame rail members 37 has engaged in the lower surface at each end thereof an attaching bolt 41 having a washer 42 engaged thereon. Secured on the inner side of the head end of each of the frame rails 37 is a stop or spacing block 43. Pivoted to the head end of each of the side frame intermediate rails 37, by means of a wing bolt 44, is the inner end of a side frame head rail 45 provided with a dowel receiving opening 46 near the outer end of the inner side thereof.

Pivottally supported on the outer surface near one end of each of the head side rails 45 is the upper end of a head leg 47 constructed of metal or other suitable material. Rigidly secured on the outer surface of each of the head rails 45, near one end and adjacent the lower edge of the head rail, is a stop member or block 48 for limiting the swing of the leg 47 when the same is swung downwardly to a supporting position for use, as illustrated in Figures 1 and 2. To prevent accidental collapsing of the legs 47, a spring-controlled stud or pin 49 (Figure 12) is mounted in the head rail 45 to project from the inner side thereof to engage the side of a leg 47 opposite the stop block 48. To swing the leg 47 into a closed position adjacent the head rail 45, it is only necessary to depress the spring-controlled pin 49.

Rigidly secured to the inner face of the foot end of each of the intermediate side frame rails 37 is a spacing block 50. Pivottally supported on the spacing block 50, by means of a wing bolt 51, is the inner end of a side frame foot rail 52 constructed of wood or other suitable material. The inner face of the outer end of the side frame foot rail 52 is provided with a recess or opening 53 for removably receiving one end of the foot dowel bar 36. Pivottally supported at one end on the inner side of each of the frame foot rails 52 is one end of a foot leg 54, the swing of which is limited by means of a stop block or stop nut 55. To prevent accidental collapsing of the foot leg 54, each of the foot rail frame members 52 is provided with a spring controlled detent or pin 49 similar in construction to that illustrated in Figure 12.

For the purpose of securing the side margins of the head and foot mattress sections 31 and 32 respectively to the respective side frame head rails 45 and foot rails 52, the side margins of the mattress head and foot sections are provided with oval fastener eyelets 56 for the removable reception of oval curtain fasteners 57 secured upon the top surfaces of the side frame rails 45 and 52, as illustrated in Figure 9.

When the combination bed and chair is not in use, the base section is adapted to be collapsed, as illustrated in Figure 4, and the bed or mattress section is adapted to be collapsed, as illustrated in Figure 8, so that both of the collapsed sections may be placed side by side within a suitcase section 2, as illustrated in Figure 2. The opposite half of the suitcase, namely, the section 1 is adapted to have removably engaged therein a folding and collapsing chair 58 of the type illustrated in my co-pending application for patent entitled "Chair," filed of even date herewith, Serial No. 238,997. Several of the collapsed chairs 58 may be carried in the suitcase section 1, if desired.

From the assemblage illustrated in Figure 2, it will be noted that a convenient furniture combination is provided in the collapsible sectional combination bed and chair and the collapsible and folding type of chairs which may be conveniently stored and transported in a combination suitcase and table to provide a very convenient camping or beach outfit.

To set up the combination bed and chair into the assembled relationship ready for use, as illustrated in Figure 1, the base unit, illustrated in collapsed form in Figure 4, is first opened up by dropping the legs 17 into a vertical position and projecting the latch bolts 18 from the dotted line position illustrated in Figure 6 into the full line

position to prevent the base legs from accidentally collapsing. The side rails 4 are now separated, thereby opening up the transverse hingedly connected brace rails 22 and simultaneously stretching the brace straps 29. With the brace rails 22 in extended position, as illustrated in Figure 5, the latch bolts 25 fall into position by the action of gravity, as illustrated in Figure 7, to prevent accidental collapsing of the hingedly connected trans- 10 verse brace rails 22.

The collapsed mattress or top section is now partly opened up and placed upon the base section by engaging the attaching bolts 41 and the washer 42 in the T-slots 13 and top slots 14 provided in 15 the metal corner castings of the base section. With the middle portion of the top or mattress unit engaged to the base unit, the mattress side frame, head rails 45 and foot rails 52 are swung outwardly from the full line positions illustrated 20 in Figure 9 into the dotted line positions, and the end legs 47 and 54 are swung downwardly into the full line positions illustrated in Figure 1 to complete the opening up of the mattress frame section. The mattress end sections 31 and 32 are 25 now opened up and the dowel rod 35 is engaged to the loop portion 34 of the mattress head section 31, while the dowel bar 36 is engaged to the loop portion 34 of the mattress foot section 32. The ends of the dowels are engaged in the recesses 30 provided in the side frame rails 45 and 52, thereby transversely stretching the mattress strip within the set up mattress frame. The bed is now in a position for use, as illustrated in full lines in Figure 1.

35 For the purpose of converting the bed sections into a camp or deck chair or the like, it is only necessary to swing the head section upwardly into the dotted line position shown in Figure 1, allowing the head section legs 47 to have the lower 40 ends thereof engaged behind a stop bead or flange 59 integrally formed on the top of each of the front corner castings, as illustrated in Figure 3. The head legs 47 therefore act as braces to hold the front section in an inclined position to 45 serve as the back of a chair. The foot section is now swung downwardly from the full line position illustrated in Figure 1 into the dotted line position to provide a leg rest. The intermediate section 39 of the mattress strip now serves as the 50 seat portion of the chair construction.

It will, of course, be understood that many details of construction may be varied through a wide range without departing from the principles of the invention, and it is therefore not the purpose to limit the patent granted hereon otherwise than necessitated by the scope of the appended claims.

I claim as my invention:

60 1. A combination bed and chair comprising a collapsible base frame, latch members for holding said frame in extended position for use, base legs pivotally supported on the base frame, stop members on the base frame for limiting the swing of the base legs, shiftable bolt members on the frame 65 for holding the base legs in extended position for use, brace straps connecting the base legs on opposite sides of the base frame, a collapsible mattress frame comprising an intermediate section and end sections pivotally connected thereto, 70 means for releasably locking the mattress frame on the base frame, a foldable mattress member on the mattress frame adapted to be opened and stretched on said mattress frame, mattress legs pivotally supported on the mattress frame, and 75 means for holding the mattress legs in extended

position for use, said mattress frame and mattress member being adapted to have one of said end sections and an end portion of the mattress member raised to form a chair back braced against the base frame by a pair of the mattress frame legs, and said mattress frame and mattress member further adapted to have the opposite end section and an end portion of said mattress member lowered to form a leg rest. 5

2. A collapsible and convertible article of furniture comprising a base frame consisting of side rails and collapsible end rails, apertured corner castings connecting the side rails with the collapsible end rails, latch members carried by the end rails for engaging the corner castings to hold the collapsible end rails braced against collapsing, base legs pivotally supported on the corner castings, stop members on the corner castings for limiting the swing of the base legs, bolt members carried by the corner castings and projectable therefrom to prevent accidental collapsing of the base legs, and a convertible bed and chair top unit comprising a middle section and leg carrying end sections pivoted on the middle section, said middle section removably engaged on the base frame, said unit convertible to be used either as a bed or a chair by adjusting the end sections with respect to said middle section. 10 15 20 25

3. A collapsible and convertible article of furniture comprising a base unit consisting of frame side rails, collapsible frame end rails, apertured corner castings connecting the side rails with the end rails, latch members carried by the end rails for engaging the corner castings to hold the end rails braced in position against accidental collapsing, base legs pivotally supported on the corner castings, stop members on the corner castings for limiting the swing of the base legs, shiftable bolt members carried by the corner castings and movable into position to hold the base legs in position for use, flexible brace straps connecting the base legs on opposite sides of the article of furniture and adapted to be tensioned when the collapsible end rails are in open bracing position, a convertible combination bed and chair unit comprising a middle section and end sections pivotally connected to opposite ends thereof, and means for removably locking the middle section of the combination bed and chair unit on the corner castings of the base unit. 30 35 40 45 50

4. A collapsible and convertible article of furniture comprising a base unit consisting of frame side rails, collapsible frame end rails, apertured corner castings connecting the side rails with the end rails, latch members carried by the end rails for engaging the corner castings to hold the end rails braced in position against accidental collapsing, base legs pivotally supported on the corner castings, stop members on the corner castings for limiting the swing of the base legs, shiftable bolt members carried by the corner castings and movable into position to hold the base legs in position for use, flexible brace straps connecting the base legs on opposite sides of the article of furniture and adapted to be tensioned 60 when the collapsible end rails are in open bracing position, a convertible combination bed and chair unit, means for removably locking the combination bed and chair unit on the corner castings of the base unit, said combination bed and chair unit comprising a pair of collapsible side frame units, a mattress strip connecting the side frame units, dowel brace members removably connecting the collapsible side frame units and carried by the ends of the mattress strip. 65 70 75 80 85 90 95 98

- end leg members pivotally supported on the side frame units, and means for limiting the swing of the end leg members, said side frame units and mattress strip being adapted to have one end thereof elevated to form a chair back with the end leg members connected thereto serving as braces for the chair back and seated at their lower ends on two of the corner castings of the base unit, said side frame units and mattress strip being adapted to have the opposite end thereof dropped to form a leg rest.
5. A combination convertible bed and chair device comprising a collapsible base frame, latch members for holding the same in extended position against accidental collapsing, base legs pivoted on the base frame, means for limiting the swing of the base legs into erected position for use, bolt members for holding the base legs against accidental folding, adjustable brace straps connecting the base legs on opposite sides of the base frame, a pair of oppositely positioned collapsible mattress frame side sections, a mat-
- tress strip connecting said frame side sections, dowel brace rods engaged in the ends of the mattress strip and supported in the ends of the mattress frame side sections to hold the mattress strip in position for use, end leg members pivotally supported on the mattress frame side sections, stop members on the mattress frame side sections for limiting the swing of the end leg members, latch means on the mattress frame side sections for holding the end leg members against 10 accidental folding, and locking means carried by the mattress frame side sections and removably engageable with the base frame, said mattress frame side sections and mattress strip being adapted to have one end thereof raised to form a 15 chair back braced in position by end frame leg members the lower ends of which are seated against the base frame, said mattress frame side sections and mattress strip also adapted to have the opposite ends thereof lowered to rest on the 20 floor to form a leg rest.

ISAAK KARISH.
